velopment Company, Elizabeth, N. J., a corpo-
ration of Delaware

Application July 24, 1948, Serial No. 40,571

9 Claims. (Cl. 255—19)

1

This invention relates to blowout prevention of oil and gas wells and pertains more particularly to means for sealing a Kelly rod against well pressure in order to control the axial outlet of such wells.

In the rotary drilling of boreholes into the subsurface formations for the production of oil and gas, a drill feeding mechanism, such as a Kelly rod, is rotated by an appropriate mechanism. The drill stem is axially connected with the drill feeding mechanism so that rotation of the drill feeding mechanism produces rotation of the drill stem. The drill rotating mechanism must not only rotate the drill feeding mechanism, but must permit longitudinal movement of the drill feeding mechanism therethrough so as to permit lowering and raising of the drill stem in accomplishing the drilling. The drill feeding mechanism may be a round Kelly rod of the type having longitudinal grooves on the outer surface thereof which are gripped by elements of a bushing mounted in the drill rotating mechanism for rotating the Kelly rod. In order to provide complete control of the well pressure, it is not only necessary to provide sealing means between the well casing and the drill stem but sealing means must also be provided between the well casing and the grooved Kelly rod. Various means have been employed for providing the seal between the well casing and the drill stem which have proven satisfactory in operation. When, however, a round Kelly rod having longitudinally extending grooves on its outer surface is employed, the sealing means ordinarily employed for sealing a drill stem cannot satisfactorily be used for sealing the Kelly rod inasmuch as that portion of the sealing means adjacent the grooves of the kelly will be deformed into these grooves. Deformation of the sealing means, as described above, prevents rotation of the round, grooved kelly when in operative relation with the sealing means.

An important object of this invention is to provide a seal between a round Kelly rod having longitudinally extending grooves in its outer surface and a sealing means mounted on the well casing. A further object of my invention is to provide a sealing means having a small pressure subject area for a grooved, round kelly which will permit rotation of the kelly and at the same time permit longitudinal movement thereof. A further object is to provide a means for sealing a grooved, round kelly when employing a blowout preventer equipped with sealing means of conventional design.

2

Briefly, this invention concerns the provision of a member adapted to rotate with a grooved, round Kelly rod, the said member having vertically extending fingers, the inner surfaces of the fingers fitting slidably and sealably into the grooves of the kelly and the outer surfaces of the fingers cooperating with the outer surface of the kelly to define a cylindrical surface coinciding with the outer surface of the kelly. With this arrangement the conventional sealing means, such for example as rams, of a blowout preventer may be closed around the kelly adjacent the aforementioned fingers thus providing a positive seal so that no well fluid escapes from the well head past the kelly. Of course, with this arrangement, the Kelly bar may be rotated while in operative relation with the sealing means and therefore sealed against well pressure and may also be moved vertically while so sealed in accordance with the demands of the drilling operation. Another advantage of this arrangement is that the fingers which slidably and sealably fit the grooves of the kelly present a very small area which is exposed to the pressure exerted by the well fluid and, consequently, are subjected to a relatively low total pressure. Inasmuch as the total pressure is of a low order of magnitude, the upward thrust produced by the fingers by reason of the pressure exerted by the well fluid may easily and simply be absorbed by suitable means. This is a distinct advantage over the prior art devices designed for providing a seal around a rotating and longitudinally movable kelly. For example, a round grooved kelly, such as I employ, having an overall diameter of 6 inches and provided with six grooves having a radius of $\frac{3}{4}$ inch and a depth in the kelly of approximately $\frac{5}{8}$ inch would require six fingers presenting a total area of approximately 1 sq. in. to the well fluid. Assuming a well pressure in the order of 2,000 lbs. per sq. in., the total pressure tending to force the fingers upwardly would be in the order of 2,000 lbs. This small thrust can easily be taken care of by employing fingers of the proper strength and mounting means for the fingers of the proper design without resorting to cumbersome arrangements which have been employed in the prior art devices for overcoming the tremendous upward thrusts involved.

Other objects and advantages of my invention will be apparent from the following description and the accompanying drawing wherein:

Fig. 1 is a vertical section through a grooved Kelly sealing mechanism in active sealing relation with a grooved kelly and the rams of a blow-

out preventer, embodying the features of the present invention;

Fig. 2 shows the section on the line II—II of Fig. 1;

Fig. 3 is a perspective view of a grooved Kelly sealing mechanism;

Fig. 4 is a section on the line IV—IV of Fig. 3;

Fig. 5 is a perspective view of another embodiment of a grooved Kelly sealing means;

Fig. 6 is a vertical section through another embodiment of a grooved Kelly sealing mechanism;

Fig. 7 is a view in elevation of a portion of the Kelly bushing shown in Fig. 6;

Fig. 8 is a side view in elevation of the bushing shown in Fig. 7;

Fig. 9 is a section on the line IX—IX of Fig. 6;

Fig. 10 is a section on the line X—X of Fig. 6;

Fig. 11 is a plan view of another embodiment of a grooved Kelly sealing mechanism together with a mounting means for same; and

Fig. 12 is a vertical section on the line XII—XII of Fig. 11.

Referring first to Figs. 1 to 5, inclusive, of the drawing, a round Kelly bar 10 having a plurality of longitudinally extending grooves 11 is mounted for rotation about its axis in a Kelly drive bushing C, bushing C carrying therein circulating balls 13 which are adapted to fit into grooves 11 of Kelly bar 10 for transmitting thereto the rotary motion of rotary table 14 which carries bushing housing 14' thereon with Kelly drive bushing C mounted in said housing. Kelly drive bushing C is removably held in place within bushing housing 14' by means of retaining member 12. Kelly drive bushing C is also adapted to permit Kelly bar 10 to move longitudinally therethrough with ball bearings 13 in engaging contact with longitudinally extending grooves 11. A detailed description of the structure and operation of Kelly drive bushing C and Kelly bar 10 may be found in my copending application Serial No. 66,772, filed December 22, 1948. For the purposes of this invention, it is sufficient that Kelly drive bushing C transmit rotative motion to kelly 10 while permitting longitudinal movement thereof. Kelly 10 is also shown as extending through a blowout preventer 15 and the upper portion of a wellhead 16. In the drawing blowout preventer 15, mounted adjacent kelly 10 with its axis coinciding with the axis of the kelly, has been shown diagrammatically as consisting of a housing 17 engaged with a wellhead 16, the said housing defining an annular recess 18 adapted to receive oppositely disposed rams 19 consisting of a deformable material, such as rubber, for providing a seal with the outside cylindrical surface of a tubular member when said rams are brought into operative contact with said surface by a suitable mechanism of conventional design, not shown. As will be noted in Fig. 2, rams 19 define an inner surface 20 which is cylindrical in form when the said rams are brought into operative contact with a member having an outer cylindrical surface.

As will be noted from Fig. 1, grooves 11 extend to the upper extremity of kelly 10 and terminate at their lower ends in surface 11', which surface is preferably normal to the surface of grooves 11.

The Kelly groove sealing mechanism, perspective shown in Fig. 3 and designated as assembly A, consists of a circular framework 21 defining a central passage 22 of sufficient diameter to permit passage of kelly 10 therethrough having vertically extending fingers 23

arranged with the axes of said fingers on the circumference of central opening 22. The upper surface of circular framework 21 defines a plurality of threaded holes 4. Fingers 23 are spaced on the circumference of central passage 22 so as to coincide with longitudinally extending grooves 11 of Kelly rod 10. The inner surface 24 of fingers 23 are shaped to conform to the configuration of grooves 11. In the drawing inner surface 24 of fingers 23 is shown as arcuate in form to conform to the arcuate configuration of grooves 11 although it will be understood that grooves 11 may be of any desired configuration and that surface 24 of fingers 23 are to be of corresponding configuration. A thin coating of deformable material 25, such for example as rubber, covers surface 24 so as to provide a fluid-tight seal between surfaces 24 and the surface formed by grooves 11 when the fingers are in operative relation with the grooves. It will be understood, of course, that deformable material 25 may consist of any deformable material which will provide a fluid-tight seal between surface 24 and the surface formed by groove 11 when finger 23 is firmly pressed into groove 11. Outer surfaces 26 of fingers 23 must necessarily be arcuate, the curvature being such that outer surfaces 26 cooperate with the outer surface of the kelly, when deformable material 25 is in sealing contact with groove 11, to form a cylindrical surface. The surface formed by outer surface 26 of fingers 23 and the outer surface of kelly 10 must necessarily be cylindrical in form so that the said surface may be rotated while in sealing contact with surfaces 29 of rams 19. While the drawing shows six vertically extending fingers 23, it will be understood that the number of fingers 23 must necessarily correspond to the number of grooves 11 on the outer surface of the kelly.

In Fig. 3 assembly A is shown as consisting of a continuous circular framework 21 having vertically extending fingers 23 mounted thereon, the fingers and framework forming one integral part. Instead, however, of forming one integral part, assembly A may be constructed in segments as shown in Fig. 5. In Fig. 5 circular framework 21 is shown as consisting of three segments, to-wit, a, b, and c, although it will be understood that circular framework 21 may be divided into any number of desired segments. Fig. 5 also shows fingers 23 mounted on circular framework 21 with the fingers equally divided between segments a, b and c. Each of segments a, b and c define a threaded hole in their upper surface adapted for receiving a threaded bolt or screw. As a matter of fact, the embodiment of assembly A shown in Fig. 5 is identical with the embodiment of assembly A shown in Fig. 3 except for the fact that circular framework is split into segments instead of appearing as a continuous ring. The modification shown in Fig. 5 is secured in place on the housing 17 of blowout preventer 15 similarly to the modification shown in Fig. 3.

Longitudinal movement of the grooved Kelly sealing mechanism is prevented by removably secured roller bearing 27 which is mounted on an outwardly extending ring portion of circular framework 21 and on housing 17 of blowout preventer 15. Bearing 27 is held in position by retaining ring 29 defining upper surface 29' which tapers downwardly and outwardly and by ring 2 which is secured to circular framework 21 by means of screws 3 which are adapted to pass through ring 2 and to threadedly engage

with threaded holes 1 in the upper surface of circular framework 21. Bearing 27 permits assembly A to rotate with kelly 10 when the kelly is rotated while rams 19 are in position for sealing the kelly.

Locking ring 29 is held in place by means of a releasable locking means designated as assembly B which includes a housing 30 secured to the housing 17 of blowout preventer 15 by suitable means such as cap screws 31. Housing 30 defines a passage, rectangular in shape, in which is slidably arranged a movable cam member 32. The outer surface of cam member 32 is generally rectangular in shape which allows it to move slidably within housing 30 while the outer end surface thereof defines a slanting or wedge surface 33. Cam member 32 defines a central cylindrical cavity which is adapted to carry piston 34 slidably therein. Piston 34 is attached to piston rod 35 which, in turn, is secured to housing 30.

A packing 36 is mounted on piston 34 to prevent leakage between the exterior surface thereof and the cylindrical wall of cam member 32. Another packing 37 is provided around piston rod 35 to prevent leakage around the piston rod. The portion of the cavity defined by a member 32 between said piston 34 and packing 37 is designated as 38 while the portion of the cavity between piston 34 and the end of member 32 defining wedge surface 33 is designated as 39. Piston rod 35 defines a central passage 40 extending longitudinally through said piston rod and communicating with cavity 39 and connected through conduit 41 to a suitable source of hydraulic pressure, not shown. Cam member 32 defines a side port 42 fluidly connecting with cavity 38 and connected through conduit 43 to a suitable source of hydraulic pressure, not shown.

It will be seen that by exerting pressure in cavity 39 while releasing pressure from cavity 38, cam member 32 may be pushed toward locking ring 29 to force wedge surface 33 of cam member 32 into contact with tapered surface 29' of ring 29. With surface 29' and surface 33 in contact, the fluid pressure exerted against cam member 32 biases retaining ring 29 downwardly thus holding bearing 27 and, in turn, assembly A in place. With assembly A so placed, rams 19 of blowout preventer 15 may be closed about kelly 10 and fingers 23 of assembly A to provide a fluid-tight seal between rams 19 and the kelly. While rams 19 are so closed, kelly 10 may be rotated therein and may simultaneously be moved longitudinally.

By exerting pressure in cavity 38 while releasing pressure in cavity 39, cam member 32 may be pushed away from retaining ring 29 thereby disengaging surface 33 of cam 32 from surface 29' of retaining ring 29. With cam 32 in the aforementioned retracted position, retaining ring 29 may be lifted from its position holding bearing 27 in place, bearing 27 may then be removed from its seat on outwardly extending ring portion 28 of circular framework 21 and assembly A may be moved vertically along kelly 10 with fingers 23 in grooves 11. In this manner assembly A may be moved upwardly on kelly 10 to any desired or convenient point.

In the drawing two hold-down assemblies B are shown. It will be understood, of course, that the number of such assemblies employed is not critical and that one or more of such assemblies may be utilized with satisfactory results. Actually, I prefer to employ three such assemblies radially spaced with respect to bearing 27 so as

to minimize the canting of said bearing in its seat. Of course, a larger number would also reduce the tendency of bearing 27 to cant, but ordinarily it will be found unnecessary to employ 5 more than three of such assemblies.

It will be further understood that assembly B need not be hydraulically operated. As a matter of fact, any releasable latching means may be employed for holding ring 29 in place and may be 10 either hand operated or power operated, although I prefer to employ a hydraulically operated latching means for convenience in quickly inserting or removing assembly A. When the sealing mechanism shown in Figs. 1 and 3 is employed 15 for providing a seal between Kelly rod 10 and rams 19 of blowout preventer 17, assembly A shown in Fig. 3 is inserted over the upper end of Kelly rod 10 with fingers 23 pointing downwardly and fitting slidably into grooves 11. 20 Bearing 27 is fit into retaining ring 29 after which bearing 27 and ring 29 is passed over the upper end of kelly 10 with surface 29' of retaining ring 29 facing upwardly. Ring 2 is then passed over the upper end of kelly 10, after which ring 2 is 25 affixed to assembly A by means of bolts 3 which are passed through ports 3' and threadedly engaged in holes 1 defined by assembly A. In this manner bearing 27 is clamped between outwardly extending portion 28 of assembly A and ring 2 30 with retaining ring 29 mounted on the outer periphery of bearing 27. Assembly A, bearing 27, retaining ring 29, ring 2 and bolts 3, after being assembled in the aforementioned manner, may then be moved along the kelly with fingers 23 in 35 sliding contact with grooves 11. Kelly rod 10 is then suspended by a suitable means and the lower end inserted through the central opening of rotary table 14, blowout preventer 15 and wellhead 16 until the lower edge of retaining ring 29 abuts 40 against housing 17 of blowout preventer 15. Retaining ring 29 may then be locked in place by cam 32 of assembly B in the manner hereinbefore described. Bushing C may then be inserted over the upper end of kelly 10 and lowered 45 into place in rotary table 14. With the sealing mechanism in the locked position kelly bar 10 may be rotated by means of rotary table 14 and bushing C and when so rotated, assembly A, ring 2, bolts 3 and the inner race of bearing 27 will 50 also rotate. When it is desired to seal kelly 10 against well pressure, rams 19 of blowout preventer 15 are moved to the closed position in contact with kelly 10, thus pressing fingers 23 firmly within grooves 11. Inasmuch as the outer surface 26 of fingers 23 cooperate with the outer surface of kelly 10 to define a cylindrical surface 55 in sealing contact with rams 19, kelly 10 may be rotated and moved longitudinally within rams 19, thus preventing the escape of well fluid past the 60 kelly.

When kelly bar 10 is to be removed from wellhead 16 and blowout preventer 15, as for example, when another section of drill pipe is to be added, cams 32 of assembly B are retracted as hereinbefore described and kelly bar 10 is raised until the lower ends of fingers 23 abut against surface 11'. Continued raising of the kelly will consequently raise assembly A together with ring 2, bearing 27, retaining ring 29 and bolts 3 until such time as the sealing mechanism abuts against the lower edge of bushing C. Continued raising of kelly 10 will then of course also lift bushing C from its seat in rotary table 14. Kelly bar 10 may then be raised to a sufficient height to insert an 65 additional section of drill pipe, after which Kelly 70

75

bar 10 may be connected thereto. Kelly bar 10 may then be lowered until bushing C again assumes its seat in rotary table 14 and ring 29 abuts against housing 17 of blowout preventer 15, at which time cam 32 may be moved into the closed position for latching the sealing mechanism in position as hereinbefore described.

The modification of assembly A shown in Fig. 5 is mounted on Kelly bar 10 adjacent blowout preventer 15 in a manner similar to that described in connection with the modification shown in Fig. 3. The only difference between the two modifications is that in the case of modification shown in Fig. 5 assembly A need not be slipped over the upper end of kelly 10 inasmuch as assembly A is split into segments a, b and c. Instead, segments a, b and c may each be moved laterally into position on the outer surface of kelly 10 to form a circular framework around the kelly. After bringing segments a, b and c into position on the kelly, these segments are operatively joined with bearing 21, ring 2, bolts 3 and ring 29 in a similar manner to the manner hereinbefore described for assembling these parts with assembly A shown in Fig. 3.

Figs. 6 to 10, inclusive, show another embodiment of the grooved Kelly sealing mechanism of my invention. In this embodiment, the vertically extending fingers adapted to slidably and sealably fit into the grooves of a grooved kelly are attached directly to the lower end of the Kelly bushing thereby permitting the rotation of the fingers with the kelly without the necessity of providing a bearing and hold-down means as shown in Fig. 1.

Referring to Figs. 6 to 10, inclusive, 50 designates a round Kelly bar having longitudinally extending grooves 51. Grooves 51 terminate at their lower end in surface 52 which is normal to the surface formed by grooves 51. Surface 52 is normal to the surface formed by groove 51 instead of being dished, as is normally the case, for a purpose which will hereinafter appear. Kelly 50 is shown arranged within blowout preventer 53 and casinghead 54 and mounted within the central passage 9 formed by Kelly drive bushing C'. Kelly drive bushing C' consists of housing 70 which is adapted to fit in the conventional manner into rotary table 71 so as to rotate in cooperation with the rotary table and is removably secured to rotary table 71 by means of bolts 70'. The inner walls of housing 70 are provided with key ways 72 adapted to receive bushing inserts 73. Inserts 73 are arranged within key ways 72 so that their inner surfaces 58 cooperate to form central passage 9 in bushing C'. Inserts 73 are held against vertical movement with respect to housing 70 by means of housing cover 74 which is removably affixed to housing 70, as by means of threads 75. Bushing inserts 73 define ball bearing race 56 carrying circulating balls 57. Race 56 is so arranged that a portion of balls 57 partially project beyond the inner surface 58 of inserts 73, the projecting portion of balls 57 fitting into grooves 51 of Kelly rod 50. Consequently, when rotary table 71 is rotated, Kelly drive bushing C' also rotates thereby imparting rotation to Kelly rod 50 by means of the engagement of balls 57 with grooves 51. Kelly rod 50 is also free to move longitudinally through Kelly drive bushing C' and when Kelly rod 50 is moved longitudinally, balls 57 circulate in ball race 56.

Mounted on the lower inner edge of each of bushing inserts 73 is a vertically extending finger 59, each finger being adapted to fit slidably and

sealably in a groove 51 of kelly 50 as shown in Figs. 7, 8 and 9. It will be understood, however, that a sufficient number of fingers 59 must be affixed to the lower inner edge of inserts 73 to provide a finger for each groove 51 of kelly 50 as shown in Fig. 10. Thus a sufficient number of inserts 73 must be provided in housing 70 to carry sufficient fingers for the aforementioned purpose even though the said inserts are not provided with a ball bearing race carrying ball bearings as shown in Figs. 7, 8 and 9. It will be further understood that the structure shown in Figs. 7, 8 and 9 for engaging and transmitting rotative movement to the kelly forms no part of this invention. As a matter of fact, any Kelly bushing which will transmit rotative movement to the kelly while permitting longitudinal movement of the kelly therethrough may be employed in accordance with the present invention. Fingers 59 are disposed on the circumference of central opening 9 of such a bushing at the lower end thereof so as to fit sealably and slidably in each of the grooves of the kelly. Fingers 59 are of sufficient length to extend along grooves 51 to at least a point below the lower edge 60 of rams 53' carried by blowout preventer 53.

The inner surface 61 of fingers 59 are shaped to conform to the configuration of grooves 51. In the drawing inner surface 61 of fingers 59 is shown as arcuate in form to conform to the arcuate configuration of grooves 51, although it will be understood that grooves 51 may be of any desired configuration and that surface 61 of fingers 59 is to be of corresponding configuration. A thin coating of deformable material 62, such for example as rubber, covers surface 61 so as to provide a fluid-tight seal between surface 61 and the surface formed by grooves 51 when fingers 59 are tightly pressed into said grooves. It will be understood, of course, that deformable material 62 may consist of any deformable material which will provide a fluid-tight seal between surface 61 and the surface formed by grooves 51 when fingers 59 are firmly pressed into grooves 51 while still permitting Kelly rod 50 to move longitudinally with respect to said fingers. Outer surfaces 63 of fingers 59 must necessarily be arcuate, the curvature being such that the outer surfaces 63 cooperate with the outer surface of the kelly to form a cylindrical surface when fingers 59 are in sealing slidable contact with grooves 51. The surface formed by outer surfaces 63 of fingers 59 and the outer surface of kelly 50 must necessarily be cylindrical in form so that the said surface may be rotated in sealing contact with surface 64 of rams 53'. The lower end surface 65 of fingers 59 is normal to inner surface 61 of the fingers so that surface 65 can make contact with surface 52 at the lower end of grooves 51. Fingers 59 are made to possess sufficient strength to support the weight of Kelly drive bushing C' on abutment of surface 65 on surface 52.

When it is desired to seal kelly 50 against the passage of well fluid from casinghead 54, rams 53' are closed tightly around kelly 50. The pressure of rams 53' forces the deformable material 62 carried by the inner surface 61 of fingers 59 into close contact with the surface defined by grooves 51 and also provides a fluid-tight seal around the surface defined by outer surface 63 of fingers 59 and the outer surface of kelly 50. Thusly, the closing of rams 53' prevent the passage of well fluid from casinghead 64 inasmuch as an effective seal is provided between kelly 50

and blowout preventer 53. At times, such for example as when an additional string of drill pipe is to be added, it will be necessary to withdraw the kelly from the casinghead and the blowout preventer. During such an operation, the Kelly drive bushing employed is conventionally permitted to remain on the Kelly bar and after the Kelly bar is disconnected from the drill pipe, the Kelly bar and the Kelly drive bushing are lifted from the hole. When such an operation is to be carried out with the embodiment shown in Figs. 6 to 10, inclusive, the Kelly bar itself is raised in the conventional manner, bolts 70', which removably secure bushing C' to rotary table 71, having been removed. After the Kelly bar has been raised a sufficient distance, end surface 65 of fingers 59 abuts against surface 52 at the lower terminus of each groove 51. Continued raising of the Kelly bar will result in lifting Kelly drive bushing C' from its seat in the rotary table. Inasmuch as fingers 59 are made of sufficient strength to carry the weight of Kelly drive bushing C' in the aforescribed manner, Kelly rod 50, together with Kelly drive bushing C', may be moved to any desired point on the derrick, such for example as the rat hole. Since fingers 59 are made to fit closely into grooves 51, bushing C' and fingers 59 will retain their intended positions with respect to Kelly bar 50 and consequently Kelly bar 50, together with bushing C', may be returned to their normal positions in the well at the desired time without displacing fingers 59 from grooves 51.

Inasmuch as fingers 59 shown in modification of Figs. 6 to 10, inclusive, are affixed to the lower end of bushing inserts 73, the sealing mechanism of this modification is brought into operative position within blowout preventer 53 at the same time it is desired to render bushing C' operative for rotating Kelly bar 50.

Figs. 11 and 12 show still another modification of the sealing means and a mounting means therefor which may be employed in accordance with my invention. Rather than employing the assembly A of Figs. 3 or 5 in conjunction with the hold-down means (assembly B) and the bearing arrangement shown in Fig. 1, the modification which is shown in Figs. 11 and 12 may be instead employed. In Figs. 11 and 12 circular framework 100 is shown as consisting of three segments, to-wit, 100a, 100b and 100c, although it will be understood that circular framework may be divided into a larger number of segments if desired. Each of the ends of segments 100a, 100b and 100c are adapted to receive a pin 101 for joining the said segments together to form circular framework 100. Circular framework 100 defines a central passage 102 of sufficient diameter to permit passage of kelly 10 of Fig. 1 therethrough and carries vertically extending fingers 103 arranged with the axis of said fingers on the circumference of central opening 102. Fingers 103 are spaced on the circumference of central passage 102 so as to coincide with longitudinally extending grooves 11 of kelly 10. The inner surface 104 of fingers 103 is shaped to conform to the configuration of grooves 11. In the drawing inner surface 104 of fingers 103 is shown as arcuate in form to conform to the arcuate configuration of groove 11 of the kelly shown in Fig. 1 although it will be understood that grooves 11 may be of any desired configuration and that surface 104 of fingers 103 is to be of corresponding configuration. A thin coating of deformable material 105, such, for example, as rubber, covers surface 104 so as to

provide a fluid-tight seal between surfaces 104 and the surface formed by grooves 11 when said fingers are placed in operative relation with the said grooves. The outer surfaces 106 of fingers 103 must necessarily be arcuate, the curvature being such that the outer surfaces 106 cooperate with the outer surface of kelly 10 when deformable material 105 is in sealing contact with curves 11 of kelly 10, to form a cylindrical surface. The surface formed by outer surface 106 of fingers 103 and the outer surface of kelly 10 must necessarily be cylindrical in form so that the said surface may be rotated in sealing contact with surfaces 20 of rams 19 shown in Fig. 1. While the drawing shows six vertically extending fingers 103, it will be understood that the number of fingers must necessarily correspond to the number of grooves on the outer surface of the kelly which is to be sealed.

20 Mounted on the outer surface of circular framework 100 is a plurality of radially spaced axles 107, the longitudinal axes of which pass through the geometric center of circular framework 100. Mounted on each of axles 107 are 25 beveled roller bearings 108 which are adapted to rotate about the axes of said axles. Each of said roller bearings 108 may be tapered outwardly as shown.

Hold-down assembly D consists of hold-down ring 109, bolts 110 and retaining nuts 111. Hold-down ring 109 is shown as consisting of two segments 109d and 109c, although it will be understood that ring 109 may be divided into a greater number of segments. Segment 109c defines a 30 pair of outwardly extending ears 112 at each of its ends, each ear defining a port 113 while segment 109d defines a single ear 114 at each of its ends, ear 114 defining a port 115 which mates with ports 113 in ears 112. Segments 109c and 109d 35 are joined together to form ring 109 by mating ports 113 and 115 and passing bolt 110 through said ports.

Ring 109 defines on its inner surface an annular recess or track 116 for receiving rollers 108. The upper surface 117 of annular recess 116 is beveled downwardly and outwardly while the roller surface 118 is beveled upwardly and outwardly. Surfaces 117 and 118 are beveled so as to receive rollers 108.

50 In employing the modification shown in Figs. 11 and 12, in connection with kelly and blowout preventers shown in Fig. 1, segments 100a, 100b and 100c are placed on kelly 10 with fingers 103 fitted into grooves 11. The aforementioned segments are then joined by means of pins 101. Segments 109c and 109d are then placed around ring 100 so that rollers 108 engage with track 116 as shown in Fig. 12. Segments 109c and 109d 55 are then joined by means of bolts 110 and retaining nuts 111. This assembly is then moved downwardly along the kelly to a point just above the blow-out preventers at which time bolts 110 are threadedly engaged with threaded wells 119 provided in housing 17 of blow-out preventers 15. A spacer 120 may be provided between ring 109 and housing 17. When the assembly is mounted in the aforescribed manner, circular framework 100, together with fingers 103, may be rotated in cooperation with the kelly while ring 109 60 provides a mounting on the blow-out preventer for roller bearings 108 carried by framework 100.

When it is desired to remove kelly 10 shown in Fig. 1 from the axis of the borehole for any reason, ring 100, fingers 103 and ring 109 may be

11

permitted to remain on the kelly by merely disengaging retaining nuts 111 from bolts 110, thus permitting ring 109 to slip off the said bolts. If it is desired that ring 109 also remain on the kelly, temporary pins, not shown, may be inserted in ports 113 and 115 to hold 109c and 109d together. Ordinarily, however, segments 109c and 109d will be temporarily removed from their position on the kelly until the kelly is again returned to its position in the borehole. When the kelly is so returned and since framework 100 and fingers 103 are already mounted on the kelly, all that remains to be done to secure framework 100 above blow-out preventer 15 is to again assemble ring 109 in the manner hereinbefore described and to secure ring 109 over bolts 110 by means of retaining nuts 111.

The nature and objects of the present invention having been fully described and illustrated, what I wish to claim as new and useful and to secure by Letters Patent is:

1. A device for providing a fluid-tight seal between a grooved round kelly and the sealing means of a blowout preventer adapted to seal circumferentially a cylindrical surface comprising, in combination, a member defining a central opening concentric with the axis of the kelly and carrying vertically extending fingers, each finger defining an inner and outer surface, said fingers being arranged with their axes on the circumference of said central opening and having their inner surfaces fitting slidably and sealably in the grooves of the kelly and their outer surfaces cooperating with the outer surface of the kelly to define a uniform cylindrical surface.

2. A device for providing a fluid-tight seal between a grooved round kelly and the sealing means of a blow out preventer adapted to seal circumferentially a cylindrical surface comprising, in combination, a member mounted for rotation with the kelly defining a central opening concentric with the axis of the kelly and carrying vertically extending fingers, each finger defining an inner and outer surface, said fingers being arranged with their axes on the circumference of said central opening and having their inner surfaces fitting slidably and sealably in the grooves of the kelly and their outer surfaces cooperating with the outer surface of the kelly to define a uniform cylindrical surface adjacent the sealing means of the blowout preventer.

3. A device for providing a fluid-tight seal between a grooved round kelly and the sealing means of a blowout preventer adapted to seal circumferentially a cylindrical surface comprising, in combination, a circular framework defining a central opening concentric with the axis of the kelly and carrying vertically extending fingers, each finger defining an inner and outer surface, said fingers being arranged with their axes on the circumference of said central opening and having their inner surfaces fitting slidably and sealably in the grooves of the kelly and their outer surfaces cooperating with the outer surfaces of the kelly to define a uniform cylindrical surface, a mounting adapted to be removably secured to a blowout preventer and bearings arranged to support said framework for free rotation on said mounting.

4. A device for providing a fluid-tight seal between a grooved round kelly and the sealing means of a blowout preventer adapted to seal circumferentially a cylindrical surface comprising, in combination, a plurality of arcuate segments carrying vertically extending fingers, each

12

finger defining an inner and outer surface, said segments being adapted to be joined to form a central framework defining a central opening concentric with the axis of the kelly with said fingers arranged with their axes on the circumference of said central opening and having their inner surfaces fitting slidably and sealably in the grooves of the kelly and their outer surfaces cooperating with the outer surface of the kelly to define a uniform cylindrical surface, a mounting means adapted to be removably secured to a blowout preventer and bearings arranged to support said framework for free rotation on said mounting.

5. A device for providing a fluid-tight seal between a grooved round kelly and the sealing means of a blowout preventer adapted to seal circumferentially a cylindrical surface comprising, in combination, a plurality of members carrying means adapted to transmit rotative movement to said kelly and to permit longitudinal movement thereof, the inner surfaces of said members cooperating to define a central opening concentric with the axis of the kelly, vertically extending fingers, each defining an inner and outer surface, mounted on the lower end of said members, said fingers being arranged with their axes on the circumference of said central opening and having their inner surfaces fitting slidably and sealably in the grooves of the kelly and their outer surfaces cooperating with the outer surface of the kelly to define a uniform cylindrical surface adapted to cooperate with the sealing means of the blowout preventer to form a fluid-tight seal between said kelly and the body of the blowout preventer.

6. A device adapted to be used when deepening a borehole provided with a casing and having a blowout preventer mounted thereon comprising, in combination, a grooved round kelly, a member defining a central opening concentric with the axis of the kelly and carrying vertically extending fingers, each finger defining an inner and outer surface, said fingers being arranged with their axes on the circumference of said central opening and having their inner surfaces fitting slidably and sealably in the grooves of the kelly and their outer surfaces cooperating with the outer surface of the kelly to define a uniform cylindrical surface adapted to cooperate with the sealing means of the blowout preventer to form a fluid-tight seal between said kelly and the body of the blowout preventer.

7. A device adapted to be used when deepening a borehole provided with a casing and having a blowout preventer mounted thereon comprising, in combination, a grooved round kelly, a circular framework defining a central opening concentric with the axis of the kelly and carrying vertically extending fingers, each finger defining an inner and outer surface, said fingers being arranged with their axes on the circumference of said central opening and having their inner surfaces fitting slidably and sealably in the grooves of the kelly and their outer surfaces cooperating with the outer surface of the kelly to define a uniform cylindrical surface adapted to cooperate with the sealing means of the blowout preventer to form a fluid-tight seal between said kelly and the body of the blowout preventer, a mounting adapted to be removably secured to the blowout preventer and bearings arranged to support said framework for free rotation on said mounting.

8. A device adapted to be used when deepening

a borehole provided with a casing and having a blowout preventer mounted thereon comprising, in combination, a grooved round kelly, a plurality of arcuate segments carrying vertically extending fingers, each finger defining an inner and outer surface, said segments being adapted to be joined to form a circular framework defining a central opening concentric with the axis of the kelly with said fingers arranged with their axes on the circumference of said central opening and having their inner surfaces fitting slidably and sealably in the grooves of the kelly and their outer surfaces cooperating with the outer surface of the kelly to define a uniform cylindrical surface adapted to cooperate with the sealing means of the blowout preventer to form a fluid-tight seal between said kelly and the body of the blowout preventer, a mounting adapted to be removably secured to the blowout preventer and bearings arranged to support said segments for free rotation on said mounting.

9. A device adapted to be used when deepening a borehole provided with a casing and having a blowout preventer mounted thereon comprising, in combination, a grooved round kelly, a plurality of members carrying means adapted to transmit rotative movement to said kelly and to permit

longitudinal movement thereof, the inner surfaces of said members cooperating to define a central opening concentric with the axis of the kelly, vertically extending fingers, each defining an inner and outer surface, mounted on the lower end of said members, said fingers being arranged with their axes on the circumference of said central opening and having their inner surfaces fitting slidably and sealably in the grooves of the kelly and their outer surfaces cooperating with the outer surfaces of the kelly to define a uniform cylindrical surface adapted to cooperate with the sealing means of the blowout preventer to form a fluid-tight seal between said kelly and the body of the blowout preventer.
